UNITED STATES PATENT OFFICE

2,411,171

KERF CUTTING DEVICE

Leon E. Simmons, Claremont, N. H., assignor to
Joy Manufacturing Company, a corporation of
Pennsylvania

Original application April 20, 1943, Serial No.
483,748. Divided and this application November
4, 1943, Serial No. 508,941.

14 Claims. (Cl. 74—251)

1

This invention relates to kerf cutting devices and more particularly to an improved chain block, strap link and hinge pin structure for a cutter chain of a coal cutting machine.

An object of the present invention is to provide an improved kerf cutting device. Another object is to provide an improved cutter chain for a coal cutting machine. A further object is to provide an improved chain block and strap link structure for a cutter chain. A still further object is to provide an improved strap link and hinge pin locking means. Still another object is to provide an improved hinge pin structure for a cutter chain, having improved means for locking the hinge pins against rotation with respect to the chain blocks. Another object is to provide an improved interlocking connection between the strap links and chain block. These and other objects and advantages of the invention will, however, herein-after more fully appear.

This application is a division of my copending application, Serial No. 483,748, filed April 20, 1943.

In the accompanying drawing there is shown for purposes of illustration one form which the invention may assume in practice.

In this drawing:

Fig. 1 is a side elevational view of a cutter chain constructed in accordance with an illustrative embodiment of the invention, a portion of the improved hinge pin structure being shown in vertical section.

Fig. 2 is a cross sectional view taken substantially on line 2—2 of Fig. 1, looking toward the front end of the chain block and showing a portion of the cutter bar.

Fig. 3 is a horizontal sectional view taken substantially on line 3—3 of Fig. 2, showing the key held in pin-locking position by the strap links.

Fig. 4 is a fragmentary view in side elevation illustrating a portion of the strap link and hinge pin lock.

Fig. 5 is a detail sectional view taken substantially on line 5—5 of Fig. 4, showing the strap links in a position to permit release of the locking key.

Fig. 6 is a perspective view of one of the hinge pins.

In this illustrative embodiment of the invention there is shown a cutter chain comprising a chain block or link 1 connected by hinge pins 2 to connecting or strap links 3. The strap links have lateral gibs 4 received in the guideways 5 of a cutter bar 6, as shown in Fig. 2. The chain block has lateral ledges 7 at its opposite sides 55

2

which overlie the outer sides of the strap links 3, in the manner shown in Fig. 2, to hold the strap links against lateral release in a manner to be later explained. The hinge pins 2 extend between the inner surfaces of guide strips 8 suitably fixed to the outer plates 9 of the cutter bar. In this illustrative construction, the hinge pins are locked against rotation relative to the chain block by locking keys 10 seated in longitudinal key slots or keyways 11 and 12 formed respectively in the pins and block. The keyways 11 extend along the exterior of the hinge pins for the entire length of the pins, as clearly shown in Fig. 6. The locking keys 10 are arranged between 10 and at their ends abut the inner surfaces at 13 of the strap links 3 during the normal running position of the cutter chain. When the strap links 3 are turned through substantially 90°, into the position shown in Fig. 4, slots 14 in the links, which 15 are normally out of registry with the key slots 12 in the block 1, are brought into registry with the key slots 12 so that the keys 10 may be driven out in an endwise direction, thereby to enable removal of the hinge pins 2. When the hinge pins 25 are removed, the strap links 3 may be readily moved out of their interlocking relation with the ledges 7 on the chain block 1. Of course, the cutter chain must be moved out of the guideways 30 of the cutter bar before removal of the pins and their keys. The chain blocks 1 have lateral lugs 15 which carry cutter bits 16, and the cutter bits are held in cutting position on the chain blocks by holders 17 held in position by set screws 18, in the manner fully described in my copending application, Serial No. 483,478 above referred to.

As a result of this invention an improved cutter chain is provided having an improved chain block and strap link structure. The novel strap link and hinge pin lock provides an effective means for holding the hinge pins against rotation relative to the blocks, thereby concentrating wear on the relatively inexpensive strap links. Also the strap links are effectually interlocked with the chain blocks. It will also be noted that 40 by the provision of the improved hinge pin construction embodying a relatively simple key and slot arrangement, the hinge pin structure of the cutter chain is greatly simplified. Other advantages of the invention will be clearly apparent to 45 those skilled in the art.

While there is in this application specifically described one form which the invention may assume in practice, it will be understood that this form of the same is shown for purposes of illustration and that the invention may be modified

and embodied in various other forms without departing from its spirit or the scope of the appended claims.

What I claim as new and desire to secure by Letters Patent is:

1. In a cutter chain, a chain block, a pair of strap links arranged at the sides of said block, said block and strap links having alined openings, a hinge pin arranged in said alined openings for pivotally connecting said strap links to the block, a key seated in longitudinal key slots in said pin and block for locking said hinge pin against rotation with respect to said block, said key arranged between the inner surfaces of said strap links.

2. In a cutter chain, a chain block, a pair of strap links arranged at the sides of said block, said block and strap links having alined openings, a hinge pin arranged in said alined openings for pivotally connecting said strap links to the block, a key seated in longitudinal key slots in said pin and block for locking said hinge pin against rotation with respect to said block, said key arranged between the inner surfaces of said strap links, and said strap links having slots extending therethrough which are normally out of registry with said key slots, and said strap links being swingable on the hinge pin into a position to bring said slots into registry with said key slots to permit endwise removal of the key.

3. In a cutter chain, a chain block, a pair of strap links arranged at the sides of said block, said block and strap links having alined openings, a hinge pin arranged in said alined openings for pivotally connecting said strap links to the block, a key seated in longitudinal key slots in said pin and block for locking said hinge pin against rotation with respect to said block, said key arranged between the inner surfaces of said strap links, and ledges on said block overlying the outer sides of said strap links to hold said links against lateral displacement from the block.

4. In a cutter chain, a chain block, a pair of strap links arranged at the sides of said block, said block and strap links having alined openings, a hinge pin arranged in said alined openings for pivotally connecting said strap links to the block, a key seated in longitudinal key slots in said pin and block for locking said hinge pin against rotation with respect to said block, said key arranged between the inner surfaces of said strap links, said strap links having slots extending therethrough which are normally out of registry with said key slots, said strap links being swingable on the hinge pin into a position to bring said slots into registry with said key slots to permit endwise removal of the key, and ledges on said block overlying the outer sides of said strap links to hold said links against lateral displacement from the block, said links upon removal of said hinge pin being releasable from said block ledges.

5. In a cutter chain, a chain block, connecting links at the sides of said block, releasable hinge elements for pivotally connecting said block and links, said block having ledgelike portions projecting from the sides thereof and engaging the outer side surfaces of said links for retaining the latter against lateral release from said hinge elements and said block in all positions of said links about their pivots, said links upon release of said hinge elements being movable bodily in a direction at right angles to the axes of said hinge elements out of engagement with said ledgelike portions.

6. In a cutter chain, a chain block, strap links at the sides of said block, said block and links

having registering bores, hinge pins received in said bores for pivotally connecting said links to said block, and keys for locking the pins against rotation with respect to said block, said keys arranged between the inner side surfaces of said links during normal running of the chain.

7. In a cutter chain, a chain block, strap links at the sides of said block, said block and links having registering bores, hinge pins received in said bores for pivotally connecting said links to said block, and keys for locking the pins against rotation with respect to said block, said keys arranged between the inner side surfaces of said links during normal running of the chain, and said links being swingable relative to said block into positions to permit release of said keys from between said side strap link surfaces.

8. In a chain, a chain link, a pair of connecting chain elements arranged at the opposite sides of said chain link, a hinge element for pivotally connecting said link and chain elements, a locking member extending lengthwise of said hinge element and having interlocking engagement with said hinge element and said chain link so that said hinge element is held against rotation relative to said chain link, said locking member being arranged and held in locking position between the inner surfaces of said chain elements with its end surfaces in end abutting engagement with said inner surfaces.

9. In a chain, a chain link, a pair of connecting chain elements arranged at the opposite sides of said chain link, a hinge element for pivotally connecting said link and chain elements, a locking member extending lengthwise of said hinge element and having interlocking engagement with said hinge element and said chain link so that said hinge element is held against rotation relative to said chain link, said locking member being arranged and held in locking position between the inner surfaces of said chain elements, one of said connecting elements being recessed near its pivot and swingable without translatory movement on said hinge element relative to said link into a position to bring solely by such swinging movement the recess into alinement with said locking member to permit endwise removal of said locking member from said hinge element.

10. In a chain, a chain link, connecting links at the sides of said chain link, hinge elements for pivotally connecting said links together, and ledgelike portions projecting from the sides of said chain link and engaging the outer side surfaces of said connecting links for retaining the latter against lateral separation from said chain link, said connecting links being movable bodily without pivoting out of engagement with said ledgelike portions upon removal of said hinge elements from said links.

11. In a chain, cooperating chain elements one of which is a connecting element, a hinge element for pivotally connecting said chain elements together, and a key interlocked with said hinge element and the other chain element for locking said hinge element against rotation with respect to said other chain element, said key being held against longitudinal displacement in one direction from its locking position by engagement of its end surface with the inner surface of said connecting chain element.

12. In a chain, cooperating chain elements one of which is a connecting element, a hinge element for pivotally connecting said chain elements together, a key interlocked with said hinge element and the other chain element for locking said

hinge element against rotation with respect to said other chain element, said key being held against longitudinal displacement in one direction from its locking position by the inner surface of said connecting chain element, and said connecting chain element being recessed near its pivot with the recess normally out of alignment with said key, and said connecting chain element being swingable without translatory movement on said hinge element relative to said other chain element into a position to bring solely by such swinging movement the recess into alignment with said key to permit endwise removal of the key.

13. In a chain, cooperating chain elements one of which is a connecting element, a hinge element for pivotally connecting said chain elements together, a key having interlocking engagement with said hinge element and the other chain element for locking said hinge element against rotation with respect to said other chain element, said key being held against longitudinal displacement in one direction from its locking position by the inner surface of said connecting chain element, and a ledgelike portion on said other chain element overlying the outer side of said connecting chain element to hold the latter against lateral displacement from said other

chain element, said connecting chain element being releasable from said ledgelike portion upon removal of said hinge element.

14. In a chain, cooperating chain elements one of which is a connecting chain element, a hinge element for pivotally connecting said elements together, a key having interlocking engagement with said hinge element and the other chain element for locking said hinge element against rotation with respect to said other chain element, said key being held against longitudinal displacement in one direction from its locking position by the inner surface of said connecting chain element, said connecting chain element having a recess near its pivot which is normally out of alignment with said key, and said connecting element being swingable on said hinge element relative to said other chain element into a position to bring the recess into alignment with said key to permit endwise removal of the key, and a ledgelike portion on said other chain element overlying the outer side of said connecting chain element to hold the latter against lateral displacement from said other chain element, said connecting chain element upon removal of said hinge element being releasable from said ledgelike portion.

LEON E. SIMMONS.
